(57) **CLAIM**

The ornamental design for an ice bucket cover, as shown and described.

DESCRIPTION

FIG. 1 is a perspective view of an ice bucket cover, showing my new design in condition of use on an ice bucket; FIG. 2 is a front elevational view of the ice bucket cover thereof, shown separately;

FIG. 3 is a rear elevational view of the ice bucket cover thereof;

FIG. 4 is a side elevational view thereof, the side opposite being a mirror image thereof;

FIG. 5 is a top plan view thereof; and,

FIG. 6 is a bottom plan view thereof.

The broken line showing of an ice bucket, ice, and bottle is for illustrative purposes only and forms no part of the claimed design.
